The ornamental design for a magnetic field generator as shown and described.

DESCRIPTION

FIG. 1 is a front perspective view of a magnetic field generator, showing the new design; FIG. 2 is a rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

The broken lines shown in the drawings of the magnetic field generator illustrate the environment of the claimed design and form no part thereof.
